OF MOLINE, ILLINOIS, A CORPORATION OF DELAWARE

GAS CALORIMETER

Application filed April 19, 1928. Serial No. 271,259.

This invention relates to gas calorimeters of the type employed for measuring the calorific value of any combustible gas, for example, producer gas. The present invention 5 concerns a calorimeter of the type generally described in my copending applications, Serial No. 93,405, filed March 9, 1926, and Serial No. 215,620, filed August 26, 1927, and more particularly concerns improvements in the 10 heat insulation of various portions of the calorimeter apparatus, as well as improvements in the electrical control system employed.

It will be appreciated that the heating 15 value of any combustible gas can be determined by ascertaining its effect on a body of liquid, such as water, when the gas is burned in heat exchanging relation with the liquid. The calorific value of a gas is ordinarily expressed 20 in British thermal units per cubic foot of gas under certain definite conditions of temperature and pressure. The B. t. u. has been defined as the quantity of heat required to raise the temperature of one pound of pure 25 water one Fahrenheit degree. It is therefore apparent that if a cubic foot of gas under standard conditions of temperature and pressure (say 60 degrees Fahrenheit and 30 inches of mercury) be burned under a cubic 30 foot of water, then, neglecting radiation losses, the calorific value of the gas expressed in B. t. u. per cubic foot is equal to the change in temperature of the water expressed in degrees Fahrenheit, multiplied by the weight 35 of a cubic foot of water. It is also true that the calorific value of a gas can be ascertained directly by noting the temperature change produced by the combustion of the gas when certain volumes of the gas are burned so as 40 to deliver their heat units to equal volumes of water.

The calorimeter embodying the present invention is preferably of the type in which equal volumes of gas are burned under equal 45 volumes of water at constant temperature and pressure whereby the calorific value of the gas can be determined by applying a single factor to the temperature rise caused by the combustion of the gas.

Means are preferably provided whereby a

continuous flow of water to a suitable heater is accompanied by a continuous flow of gas to the burner of this heater. The flow of water and gas is controlled in such a manner that the volume of water supplied to the 55 heater is equal to, or bears a predetermined relation to, the volume of gas supplied to the heater, and means are provided for insuring a constant temperature and pressure of the gas so supplied to the burner. 60

While the improved calorimeter is preferably constructed so as to deliver equal volumes of gas and water, it is to be noted that the quantity of gas or of water need not be ascertained in order to determine the calorific value of the gas. In other words, in order to determine the calorific value of the gas, it is not necessary to determine the amount or quantity of gas or of water passing through the calorimeter. The quantity 70 of gas can be ascertained if this is desired, but it is not necessary to ascertain this factor in order to determine the calorific value of the gas. 75

The embodiment of the invention herein- 75 after described in detail includes means for raising the temperature of the water to a certain predetermined value prior to the entrance of this water into the heater wherein its temperature is raised by the gas being tested. Means are also provided for bringing the gas to be tested into heat exchanging relation with the preheated water, so that the temperature of this gas is raised to approximately that of the preheated water. The 80 calorimeter of the present invention preferably includes means for circulating the water through the apparatus instead of continuously taking in a fresh supply of water which is discharged after being heated. Cooling 85 means may be provided in the circulation system for reconditioning the water after it has been heated. A pressure regulator for controlling the flow of the gas is also provided. 90

The flow of the preheated gas or water to the water heater is preferably controlled by apparatus including two containers, having a water inlet and a gas inlet. A valve and suitable pipe connections are provided between the gas inlets or ports of these two con- 100

tainers and the burner which burns the test gas, and there is also a pipe connection to the source of heated or conditioned gas described above. This valve and the pipes communicating therewith are so arranged that at one instant the gas port in one of the containers is connected to the burner and the gas port in the other container is connected to the supply of conditioned gas.

10 A valve and a plurality of pipes, similar to the valve and pipe connections just described, are arranged so as to connect the water inlets or ports of the two containers with the water heater and with the source of preheated water. The water heater referred to is the one to which heat is supplied by the burner which consumes the test gas. This last mentioned valve and associated pipe connections are arranged so that at one instant the water port in one container is connected to the water heater and the water port in the other container is connected to the source of preheated water. The water and gas valves just described should be actuated in a definite timed relation and it is entirely feasible to 15 actuate these valves by a single means, although of course separate means can be employed for this purpose. The two valves may be arranged to operate in such a manner that at one instant water is being supplied to the heater from one of the two containers, while gas is being supplied to the burner from the other container. After the major portion of the gas in the container has been supplied to the burner, the gas and water valves may be operated so as to reverse the connections and supply water to the heater from the container which previously supplied gas to the burner and to supply gas to the burner from the container which previously supplied water to the heater. Some means, such as a 20 float switch connected in circuit with an electrical device for actuating the gas and water valves, can be used for controlling the change in the connections between the containers and the other parts of the device.

25 The apparatus here disclosed includes an improved heater in which the water is heated by the gas being tested. This heater is constructed in such a manner that there is a very efficient transmission of heat to the water. A mixing chamber is provided in fairly close proximity to the heating chamber, the purpose of this mixing chamber being to thoroughly mix the heated water prior to its coming in contact with the temperature sensitive element which serves to indicate or record the temperature of the heated water. An improved feature of this mixer is a device for 30 supplying air to the stream of water flowing into the mixer. The stream of water entrains some of the air and the air bubbles serve to effect a thorough mixture of the water within the mixing chamber. It is preferred to have this air supply under control

so that by adjusting the air port the rate at which water flows into the mixing chamber can be adjusted, as well as the amount of air discharged into the mixing chamber.

35 The calorimeter preferably includes means for actuating the water and gas valves mentioned above. It is desirable to operate these valves in definite time relation and it is satisfactory to have the valve mechanism constructed in such a manner that rotation of the 40 valve member through 90° effects the necessary change in directional flow of the gas and water. The valve actuating mechanism preferably includes a motor for operating the valve together with suitable time controlled 45 means for starting and stopping the motor at predetermined intervals as hereinafter described. The motor can be arranged so as to be started and stopped by the float switches described above as being arranged within the 50 two containers which are alternately filled with water and gas.

55 Means are preferably provided in the apparatus herein disclosed for conditioning the air supplied to the burner. In order to avoid 60 any errors in the indications or record made by the instrument, it is desirable to have the air brought to a predetermined temperature before it is supplied to the burner. It is also desirable to have the humidity of the 65 air brought to a predetermined value. My invention contemplates the provision of means for conditioning the air both as to temperature and as to humidity; preferably by bringing the air into heat exchanging 70 relation with the liquid used in the apparatus and preferably in actual contact with this liquid.

75 A particular feature of the present invention comprises improved heat insulating 75 means for enclosing and segregating various elements of the apparatus and thereby maintaining the temperature of these elements at the desired values regardless of variations in the temperature of the surrounding 80 atmosphere. For example, it is desirable to thermally insulate the test gas burner from the surrounding atmosphere and from the other apparatus of the calorimeter so that practically all of the heat evolved in burning the gas may be utilized to heat the water. It is further desirable to thermally heat insulate the water heating tank and the mixing chamber so that the indicated or recorded temperatures of the water entering 85 and leaving these containers may accurately indicate the amount of heat derived from the test gas. Thus, in order that the calorimeter may accurately indicate or record the true calorific value of the gas being tested without erroneous variations due to changes in external temperature, the present invention contemplates the provision of improved heat insulating partitions and housings 90 whereby certain portions of the calorimeter 95

apparatus are thermally isolated from other portions thereof, and whereby the entire apparatus is thermally insulated from the surrounding atmosphere.

Other specific objects of the invention include improvements in the valve operating and controlling mechanism whereby sparking at electrical contacts is prevented, and improvements in the electrical control circuits and devices whereby the use of relays or similar apparatus is avoided.

Other specific objects, advantages and characteristic details of the present invention will become apparent as the description thereof progresses.

In describing the invention in detail, reference will be had to the accompanying drawings, in which:

Figure 1 is a diagrammatic representation of the apparatus comprising the calorimeter of the present invention, the approximate position of the insulating partitions and walls relative to the various elements of the calorimeter apparatus being indicated by dot and dash lines;

Fig. 2 is a side sectional view of the calorimeter cabinet showing the heat insulating partitions, walls and housing, with certain portions of the calorimeter apparatus in position therein;

Fig. 3 is an enlarged view of the electrical contact device employed in connection with the valve controlled apparatus; and

Fig. 4 is a wiring diagram of the electrical circuits of the calorimeter.

As certain elements and devices of the calorimeter of the present invention are identical with corresponding elements and devices shown and described in connection with my copending application, Serial No. 215,620, filed August 26, 1927, these portions of the calorimeter will only be briefly described herein.

A water tank 6 is provided, and is supplied with conditioned water through a pipe 5. The water so supplied preferably comprises water from the heater which has been cooled to the desired predetermined temperature by suitable apparatus and returned by a circulating pump or equivalent means. Suitable apparatus for reconditioning the water in this manner is described in detail in my copending application, Serial No. 215,620, filed August 26, 1927. An overflow pipe 8 serves to maintain a constant water level within this tank 6. A pipe 9 delivers the water from the tank 6 to the water valve 10, and two pipes 11 and 12 extend between the valve 10 and the two containers 13 and 14. Water is alternately delivered to these containers under the control of the valve 10.

The gas to be tested enters a temperature equalizing coil 7 within the tank 6 through a suitable pipe connection 15. The gas flowing in this coil 7 is brought to a temperature

approximately equal to that of the preheated water which is supplied to the tank 6 by the pipe 5. The gas leaves the coil 7 through a pipe 16, passes through a pressure regulator 17 of any well known type, and enters a gas valve 19 through a pipe 18. Two pipes 20 and 21 connect the housing of the gas valve 19 with the upper ends of the containers 13 and 14 respectively, and gas is alternately supplied to these two containers under the control of the valve 19. A pipe 22 connects the valve 19 with a burner 23, and a pipe 24 connects the water valve 10 with the heating tank 25. The gas to be tested is burned in the burner 23, and supplies its heat to the water within the tank 25. A thermometer 103 may be suitably inserted in the pipe 24 at the point 40 for the purpose of measuring or indicating the temperature of the water entering the tank 25, and a similar thermometer 104 may be used at the point 41 for the purpose of indicating the temperature of the water after it has left the container 25 and passed through the mixing chamber 28. In many cases, it is preferable to employ a differential temperature recording device for recording the difference in the water temperatures at the points 40 and 41, and as such a device is usually connected by means of wires or tubular connections, the connections 26 and 27 have been indicated at the points 40 and 41 respectively, it being understood that these connections lead to a differential recording device, thermometers or other suitable temperature responsive means.

It is often preferred to employ both mercurial thermometer and a differential temperature recording device, so that the thermometers may be used to check and calibrate the indications of the recording device. Accordingly, both the recording device connections 26 and 27 and the mercurial thermometers 103 and 104 have been shown connected to the 40 and 41 respectively.

The water is heated by the test gas in the heater tank 25, and passes through the pipe 83 to the mixing chamber 28. A short piece of piping 84 connects with the pipe 83 at a point near the mixing chamber 28 and the upper end of this piping is provided with an air intake orifice 86 which may be controlled by a suitable valve. The air intake orifice serves to control the rate of flow of liquid from the heater tank 25 to the mixing chamber 28, and further serves to permit the liquid flowing in the pipe 83 to entrain therein air bubbles which act to thoroughly mix the heated water before it comes into contact with the temperature responsive element at the point 41.

The liquid passing out of the mixing chamber 28 flows through a pipe 79 into a chamber 29 which also receives such liquid as overflows from the water tank 6 through the pipe 8. The chamber 29 is employed to condition the

air for the test gas burner 23. Air from the surrounding atmosphere enters the chamber 29 through the pipe 77 and comes into direct contact with the heated water which drips from the overflow pipe and further contacts with the water from the mixing chamber 28. In this manner, the burner air is brought to a predetermined humidity and temperature before being delivered to the burner 23 through the pipe 80. The burner 23 is enclosed in a heat insulated chamber as hereinafter described, and the conditioned air is conducted to this chamber through the pipe 80 as clearly shown in Fig. 1.

15. The method of operation of the calorimeter can be best understood by considering the manner in which the gas and water flows through the system when the valves 10 and 19 occupy one of their operating positions. 20. The water which has been brought to a predetermined temperature by suitably conditioning apparatus, and which has brought the temperature of the gas to substantially this same predetermined temperature, is free 25 to flow through the pipe connection 9, the valve 10 and the pipe 12 into the container 14. At the same time, water which has been previously supplied to the container 13 is now free to flow through the pipe 11, valve 10, 30 pipe 24 to the heater 25. While this is taking place, a predetermined volume of the test gas, which has been previously supplied to the container 14 and which is now being forced out of this container by the water entering the container through the pipe 12, flows through the pipe 21, the gas valve 19, and the pipe 22 to the burner 23. During 35 the same period of operation, gas from the coil 7 is flowing through the pipe 16, the pressure regulator 17, the pipe 18, the gas valve 19 and the pipe 20 into the container 13 to take the place of the water which is flowing out of this container and into the heater 25. It is thus apparent that the gas 40 which occupied the container 14 is being utilized to heat the water which previously occupied the container 13. This continues until the water entering the container 14 rises to a predetermined level therein and 45 actuates a float switch 32. This closes a control circuit for the motor 33' and as soon as power is supplied to this motor it operates to rotate valves 10 and 19 through an angle of 90°, thus reversing the connections to the containers 13 and 14. As soon as this happens, the water which has just flowed into the container 14 is now free to flow in the opposite direction through pipe 12, then through the valve 10 and through pipe 24 to 50 the heater 25. Also, the gas which was previously supplied to the container 13 under the control of valve 19 is now free to flow back through pipe 20 and then through the valve 19 and pipe 22 to the burner 23. Thus 55 gas from container 13 is now being used for

heating the water from container 14. The valves 10 and 19 are operated fast enough so that the supply of gas to the burner 23 is not appreciably interrupted and the flame is not extinguished. Similarly, the flow of water through pipe 24 to the heater 25 remains substantially constant, even though at one instant the water is being supplied from container 13 and then as soon as the valve mechanism operates, from the other container 14. 70 The difference in the indications of the temperature responsive means at the points 40 and 41 gives a measure of the calorific value of the gas supplied to the burner 23, and it is evident that this indication or record is 80 entirely independent of the quantity of gas or of water passing through the system. It is not necessary that the rate of flow of the gas should be any predetermined value; it is merely necessary that the volume of gas under predetermined conditions of temperature and pressure should bear a definite relation to the volume of water. It is preferred that the volume of gas should be equal to the volume of water. It is not necessary to have 85 the containers 13 and 14 of the same size, inasmuch as gas from one of these containers is used to heat water from the other and then the process is reversed so that in the complete cycle it is inevitable that equal quantities of 90 gas are used to heat equal quantities of water.

It will be understood that when the position of valve 10 is such that water can flow through pipes 9 and 11 into the container 13, the level of the water rises in this container 100 until it actuates a float switch 33 similar to the float switch 32 in container 14. As soon as this happens, the motor is again actuated to turn the valves 10 and 19 through another 90° to again reverse the connections to the 105 containers 13 and 14. The calorimeter thus continues to operate and the temperature responsive means gives a continuous indication or record of the temperature of the water before and after passing through the heater 25. 110

The improved valve operating and control apparatus and the electrical circuits of the calorimeter comprising the present invention will now be described.

115 The valve control device is generally indicated at D, and is similar to the control device shown and described in the patent application of Harold L. Parr and John H. Nelsen, Serial No. 159,223, filed January 5, 1927. The motor 33' is connected through a worm gear 35 to a vertical shaft 36 which carries a cam 37 and a valve operating arm 38. The arm 38 moves the combined valve gates of the gas and water valves 19 and 10 120 through an operating wheel 39, suitable radial arms 42 being disposed on the wheel 39 and being engaged by the arm 38 to move the valve gates through an angle of 90° during each complete revolution of the shaft 36. 125 130

The cam 37 operates a time element device which preferably takes the form of a resilient metal bellows 43, provided with a check valve 44 for permitting the rapid exhaust of air therefrom, and an adjustable needle valve 45 for permitting the gradual intake of air thereto. A push rod 46, which is operated by the cam 37, is rigidly and adjustably connected to the free end of the bellows 43, and the cam 37 and the arm 38 are so arranged on the shaft 36 that during each revolution of this shaft, the valve operating wheel 39 is first turned through an angle of 90° and the rod 46 is then moved to the left, compressing the bellows 43.

A contact device is provided in connection with the control device D, and is operated by the push rod 46. According to the present invention, this device takes the form of an enclosed switch, that is, a switch in which the contacting parts are protected from the surrounding atmosphere. In the embodiment of the invention disclosed, the contact device comprises a pivotally mounted enclosed mercury switch 47 provided with two pairs of contacts 48 and 49 as most clearly shown in Fig. 3. This mercury switch is of usual and well known construction, comprising a tube 50 of glass or other suitable material which is carried by an arm 51 pivoted to the frame of the control device at the point 52. The mercury switch is connected to the push rod 46 by a pin 53 secured to the arm 51 and carried between two stops 54 which are suitably adjustably secured to the rod 46 as clearly shown in Fig. 3. The contacts 48 of the mercury switch 47 are preferably included in the energizing circuit for the motor 33' and the contacts 49 thereof are arranged to control a brake on the motor shaft as hereinafter described.

Suitable braking means are preferably provided in connection with the motor 33' to prevent the momentum acquired by this motor during its operation from carrying the arm 38 beyond the position in which the valve has been turned through an angle of 90°. Any suitable form of magnetic or electric brake may be employed, and the braking means herein disclosed comprises a simplified form of magnetic brake operating directly on the motor shaft. A brake band 55, pivoted to a fixed support at 56, surrounds a suitable brake drum 57 which is fixed to the motor shaft 58. The free end of the brake band 55 is secured to the armature 59 of a suitable solenoid or electro-magnet 60. The band 55 may be resilient or otherwise arranged to spring away from the drum 52 when the magnet 60 is deenergized. It should be understood that the specific magnetic brake shown and described merely illustrates one suitable form of apparatus which may be employed, and any other well known

type of magnetic or electric brake may be used.

In accordance with the present invention, electric energy for operating the motor 33' is preferably supplied through a transformer 61 from any suitable source of alternating current AC. The transformer 61 preferably reduces the line voltage to some suitable value which is low enough to be safely controlled directly by the switches 32, 33 and 47, while at the same time being high enough to operate the motor 33'. By the use of a transformer of this type, it is unnecessary to employ relays or other auxiliary control devices, and the electric control system of the calorimeter is thereby greatly simplified. One terminal of the secondary winding of the transformer 61 is grounded at the point 62 through the wire 63, and the other terminal of this winding is connected through the wires 64 and 65 to the motor 33' and through the wires 64 and 66 to the electro-magnet 60. The control circuits have been shown in Figs. 1 and 4, and can be best understood from a description of the operation of the control device D in conjunction with the calorimeter apparatus.

When one of the containers 13 and 14, say the container 13, becomes filled with water to a predetermined level, the float switch 33 is tilted to the position shown and its contacts 67 are closed, thereby completing an energizing circuit for the motor 33', which circuit may be traced as follows:—from the grounded point 68, wire 69, contacts 67 of the switch 33, wires 70 and 71, contacts 48 of the switch 47, wires 72 and 73, the motor 33', wires 65 and 64, the secondary winding of the transformer 61 and wire 63 to the grounded point 62. Being thus energized, the motor 33' operates and turns the shaft 36 of the control device D in the direction indicated by the arrow, the arm 38 engaging one of the radial arms 42 on the valve wheel 39 and turning the gates of the valves 10 and 19 through an angle of 90°. As explained above, this operation of the valves 10 and 19 serves to connect the container 13 with the heater tank 25, to connect the water tank 6 with the container 14, to connect the upper end of the container 14 with the gas burner 23, and to connect the gas supply pipe 18 with the upper end of the container 13. Further movement of the shaft 36 of the control device D causes the cam 37 to move the push rod 46 to the left as viewed in the drawing, thus compressing the bellows 43 and tilting the switch 47 to its left hand position. The motor energizing circuit traced above is thereby broken at the contacts 48 of the switch 47, and the energizing circuit for the brake magnet 60 is completed at the contacts 49 of this switch. The brake magnet energizing circuit may be traced as follows:—from the grounded point 62, wire 63, secondary winding of the transformer 61, wires 64

and 66, windings of the magnet 60, wire 74, contacts 49 of the mercury switch 47, and the wire 75 to the grounded point 76. The energization of the brake magnet 60 tightens the brake band 55 on the drum 52 and brings the motor 33' to a stop, thus preventing the further movement of the valve wheel 39 by the arm 38. The rapid compression of the bellows 43 is permitted by the escape of air therefrom through the check valve 44, but once compressed, the bellows expands rather slowly due to the gradual entrance of air thereto through the needle valve. The needle valve is so adjusted that the expansion of the bellows tilts the switch 47 to a position to close the motor energizing circuits 48 only after the water level in the container 13 has fallen beyond the point at which the contacts 67 of the switch 33 are opened. Thus the brake energizing circuit is opened and the motor energizing contacts 48 are closed after the switch 33 is opened and before the switch 32 is closed, and consequently no immediate energization of the motor 33' results. When the liquid level in the container 14 rises to a predetermined point, the float switch 32 therein is tilted and closed, thus energizing the motor 33' through a circuit including the ground 87, the wire 88, the contacts of the switch 32, wires 89 and 71, contacts 48 of the switch 47, wires 72 and 73, motor 33', wires 65 and 64, the secondary windings of the transformer 61 and the wire 63 to the grounded point 62. This energization of the motor again causes the shaft 36 to turn, moving the valves 10 and 19 through an angle of 90° and finally opening the motor energizing circuit and energizing the brake magnet 60 by tilting the mercury switch to its left hand position. Thus, the operation of the control device D to move the gas and water valves 10 and 19 is periodically repeated as each of the containers 13 and 14 successively becomes filled with water to a predetermined level. A normally open manually operable switch 90 is preferably provided in connection with the motor energizing circuit, one terminal of this switch being grounded at the point 91, and the other terminal thereof being connected through wire 92 to wire 73 as clearly shown in Figs. 1 and 4. If, for any reason, it is desired to operate the motor 33' and change the position of the valves 10 and 19 while the switches 32 and 33 are open, an energizing circuit for the motor may be closed at the switch 90, this circuit being readily traceable on the drawings.

Due to the fact that the switch 47 of the control device D is completely enclosed, the motor energizing circuit may be directly closed and opened thereby without danger of the ignition, by sparks from the switch contacts, of any gas which may be present within the calorimeter cabinet.

Referring now more particularly to the walls

and partitions, enclosing the various parts of the calorimeter, which comprises an important feature of the present invention, the entire calorimeter is preferably enclosed in a cabinet C of suitable material such as sheet aluminum. As shown in Fig. 2, the cabinet C is preferably provided with a plurality of movable doors or closures 93 in the front wall thereof, transparent panels 94 being provided in these doors to permit the observation of the calorimeter apparatus without exposing this apparatus to the atmosphere. The interior surfaces of the side and back walls of the cabinet C, as well as the interior of the top and bottom walls thereof are preferably lined with a suitable heat insulating substance 95. It has been found that a layer of cork board about one-half inch thick is suitable for this purpose. The cabinet is preferably divided into a plurality of compartments by transverse shelves or partitions of suitable material which may or may not have heat insulating properties. These partitions are preferably arranged to thermally isolate certain portions of the calorimeter apparatus, and in this manner, any undesirable interchange of heat between certain elements of the apparatus is effectively prevented.

As shown in Fig. 2, the cabinet C is divided into three compartments, 96, 97 and 98, by two transverse partitions 99 and 100, which are formed of a suitable material which may be a heat insulating material such as bakelite. In addition to their thermal insulating features, the partitions 99 and 100 serve as convenient means on which the calorimeter apparatus may be compactly mounted. As shown in Fig. 2, the water tank 6 is mounted near the back wall of the cabinet on the lower partition 100, and extends through an opening in the upper partition 99, thus extending into both of the compartments 96 and 97. The gas and water containers 13 and 14 also occupy the compartments 96 and 97, and the lower ends thereof extend into the lower compartment 98 at points adjacent the water heater 25. The heater 25 is mounted in the lower compartment 98, and a burner compartment 101, comprising the walls 102, which may or may not be composed of heat insulating material is provided below the water heater to completely enclose, and thermally isolate the test gas burner 23 from the remainder of the calorimeter apparatus. The base of the water heater 25 extends through an opening in the top wall of the burner compartment 101 as shown, so that the hot gases from the burner come into direct contact with the heater.

In Fig. 2, certain elements of the calorimeter apparatus have been omitted to clarify the disclosure of the cabinet structure, but the arrangement of all of the apparatus relative to the cabinet compartments has been diagrammatically represented in Fig. 1, wherein

the partitions 99 and 100 and the heater compartment walls 102 have been indicated by dot and dash lines. As shown in Fig. 1, the transformer 61 and the float switch portions of the containers 13 and 14 are housed in the compartment 96, the gas pressure regulator is located in the compartment 97, and the heater tank 25, the mixing chamber 28, the control device D and the air conditioning chamber 29 are located in the compartment 98. It should be noted that the outlet pipe 80 of the air conditioning chamber 29 is connected to an opening in the wall 102 of the burner compartment 101, and in this manner the heated and humidified air from the chamber 29 is supplied to the burner 23 alone and does not come into contact with the other apparatus.

The tank 25 in which the water is heated by the test gas, and the container 28 in which the heater water is mixed, are normally at higher temperatures than the other liquid and gas containers of the calorimeter, and since the calorific value of the gas is determined by the temperature of the liquid in these containers, special heat insulating means are provided therefor to prevent the loss of heat therefrom by radiation or convection. In the present embodiment of the present invention, these insulating means take the form of sleeves or shells 103 which completely surround and enclose the vertical walls of the containers 25 and 28. The insulating sleeves 103 are preferably formed of a heat insulating material such as bakelite, and may be spaced from the containers 25 and 28 by suitable means to provide air spaces between the sleeves and the containers as shown in Fig. 2. The sleeves 103 are preferably arranged to extend from the upper surface of the top walls 102 of the burner compartment 101 to the lower surface of the transverse partition 100, so that the containers 25 and 28 are completely surrounded by walls or by heat insulating material.

From the description given, it is apparent that the entire calorimeter is effectively thermally insulated from the surrounding atmosphere, and that certain portions of the calorimeter are thermally insulated or effectively separated from each other. The arrangement of the main water tank 6 in the same compartments with the gas and water containers 13 and 14 serves to keep all of the conditioned gas and water at a substantially constant predetermined temperature before being delivered to the burner 23 and the water heater 25. The tank 6 holds a comparatively large mass of water which serves to prevent fluctuation in the temperature of the compartments 96 and 97. The containers 25 and 28 are well insulated from the remaining apparatus by the sleeves 103, and substantially the entire heat evolved in burning the test gas is thereby retained in

the water within these containers. The containers 25 and 28 are further thermally insulated from the tank 6 by the transverse partition 100. The compartment 101 in which the test gas burner 23 is enclosed effectively prevents appreciable loss of the heat evolved in burning the test gas and also provides a convenient means for supplying the conditioned air to the burner. Thus the cabinet of the present invention is adapted to permit the compact grouping of the calorimeter parts while providing effective thermal insulation for the various elements thereof.

The provision of the transformer 61 for supplying the motor energizing current at a voltage suitable for direct control by the mercury control switches is a very desirable and advantageous feature of the present invention. The use of this transformer does away with all relays and other auxiliary apparatus which are customarily employed to open and close the motor energizing circuits in a device of this type. Since no relays or other auxiliary devices are used, the danger of explosions from the ignition from gas within the calorimeter by the sparks at the contacts of such devices is eliminated. The control device D of the calorimeter of the present invention embodies improved circuit controlling and braking means. The enclosed mercury contact switch 47 of the control device provides additional safety of the operation of the calorimeter by preventing sparking at the motor energizing contacts, and the electric braking means provides a very simple and efficient method of stopping the control device at the desired point.

Although the various features of the present invention have been described in connection with a single specific construction, it should be understood that various changes, modifications and combinations of the apparatus shown may be made without departing from the scope of the invention as defined by the appended claims.

I claim:

1. In a gas calorimeter of the type in which gas is burned in heat exchanging relation with a liquid, means for storing and measuring said gas and liquid, a liquid container, a burner for burning said gas in heat exchanging relation with the liquid in said container and means for thermally insulating said storing and measuring means from said liquid container and from said burner.

2. In a gas calorimeter of the type in which a gas is burned in heat exchanging relation with a liquid, a calorimeter cabinet having heat insulating walls, a plurality of heat insulating partitions dividing said cabinet into a plurality of thermally isolated open compartments, means located in one of said compartments for storing preconditioned liquid, and means located in another of said

compartments for bringing said liquid into heat exchanging relation with burning gas.

3. In a gas calorimeter of the type in which a gas is burned in heat exchanging relation with a liquid, a cabinet having heat insulating walls, a plurality of heat insulating partitions dividing said cabinet into a plurality of thermally isolated compartments, means located in one of said compartments for storing and measuring the gas and liquid, a liquid container located in another of said compartments for receiving the measured liquid, and a gas burner located in another of said compartments for heating said liquid container.

4. In a gas calorimeter of the type in which a gas is burned in heat exchanging relation with a liquid, a calorimeter cabinet having heat insulated walls, a tank for storing pre-conditioned liquid, means for measuring the liquid and the gas, a liquid container for receiving the measured liquid, a burner located in heat exchanging relation with said container for receiving and burning the measured gas, means for thermally insulating said storage chamber from said container and from said burner, and separate heat insulated walls surrounding said burner and said container.

5. In a gas calorimeter of the type in which a gas is burned in heat exchanging relation with a liquid, a liquid container for receiving the liquid to be heated, a mixing chamber adjacent said container for receiving heated liquid from said container, a test gas burner located in heat exchanging relation with said container, heat insulating walls enclosing said liquid container and said mixing chamber, and separate heat insulating sleeves surrounding said container and said chamber respectively.

6. In a gas calorimeter of the type in which a gas is burned in heat exchanging relation with a liquid, a cabinet having heat insulating walls, a plurality of heat insulating partitions dividing said cabinet into a plurality of thermally isolated compartments, means located in one of said compartments for storing and measuring the gas and liquid, a liquid container located in another of said compartments for receiving the liquid to be heated, a mixing chamber located in the compartment with said liquid container and receiving heated liquid from said container, a test gas burner in heat exchanging relation with said liquid container and enclosed in still another compartment, and separate heat insulating sleeves surrounding said liquid container and said mixing chamber respectively.

7. In a gas calorimeter of the type in which a gas is burned in heat exchanging relation with a liquid, a calorimeter cabinet having heat insulating walls, a plurality of heat insulating partitions in said cabinet

forming a plurality of thermally isolated compartments therein, means for storing and measuring the test gas and liquid located in certain of said compartments, means for receiving the measured liquid located in another of said compartments, and a burner for burning the measured test gas located in still another of said compartments.

8. In a gas calorimeter of the type in which a predetermined quantity of gas is burned in heat exchanging relation with the predetermined quantity of liquid, a plurality of measuring containers adapted to be alternately and successively filled with and emptied of the gas and the liquid, a valve mechanism for controlling the flow of gas and liquid to and from said containers, electrically driven operating means for said valve mechanism, control switches operated by the liquid level in said containers for controlling the supply of electric energy to said operating means, and a source of electric energy directly connected to said operating means through said control switches.

9. In a gas calorimeter of the type in which a predetermined quantity of gas is burned in heat exchanging relation with the predetermined quantity of liquid, a plurality of measuring containers adapted to be alternately and successively filled with and emptied of the gas and the liquid, a valve mechanism for controlling the flow of gas and liquid to and from said containers, electrically driven operating means for said valve mechanism, control switches having enclosed contacts operated by the liquid level in said containers and by said operating means for controlling the supply of electric energy to said operating means, and a source of electric energy directly connected to said operating means through said control switches.

10. In a gas calorimeter of the type in which measured quantities of gas are burned in heat exchanging relation with measured quantities of liquid, means for measuring said gas and said liquid, valve means for controlling the flow of said gas and said liquid, an electrically operated device for operating said valve means, a cabinet having separate heat insulated compartments therein enclosing said measuring means and said control device, and electric switches having enclosed contacts controlled by said measuring means and by said valve operating means for controlling the supply of electric energy to said operating means.

11. In a gas calorimeter of the type in which measured quantities of gas are burned in heat exchanging relation with measured quantities of liquid, means for measuring said gas and said liquid, a valve mechanism for controlling the flow of said gas and said liquid to and from said measuring means, an electric motor for successively operating said

mechanism, enclosed electric contacts operated by the liquid level in said measuring means and by said motor, said contacts directly controlling the supply of current to said motor, and an electrically operated brake, controlled by one of said contacts and acting to arrest the movement of said motor after each successive operation thereof.

12. In a gas calorimeter of the type in which measured quantities of gas are burned in heat exchanging relation with measured quantities of liquid, a plurality of containers for measuring said gas and said liquid, a valve mechanism for controlling the flow of said gas and said liquid to and from said measuring means, an electric motor for operating said valve mechanism, a time controlled device operated by said motor, enclosed electric contacts operated by the liquid level in said measuring containers and by said time controlled device, and a circuit for supplying electric energy to said motor including said enclosed contacts.

13. In a gas calorimeter of the type in which a gas is burned in heat exchange relation with the liquid, a calorimeter cabinet, means for measuring the liquid and the gas, a liquid container for receiving the measured liquid, a gas burner located in heat exchange relation with said container for burning the measured gas, a partition in said cabinet for supporting said gas and liquid, measuring means and a separate partition for supporting said liquid container and for enclosing said burner.

In testimony whereof I affix my signature.
SAMUEL W. PARR.
